FIG. 3

UNITED STATES PATENT OFFICE

2,531,176

THREAD CONTROL FOR WEFT
REPLENISHING LOOMS

Richard G. Turner, Worcester, Mass., assignor to
Crompton & Knowles Loom Works, Worcester,
Mass., a corporation of Massachusetts

Application May 17, 1949, Serial No. 93,792

6 Claims. (Cl. 139—257)

1

This invention relates to improvements in thread control means for weft replenishing looms and it is the general object of the invention to provide simple means by which the thread of a freshly transferred bobbin can be placed favorably for threading of the shuttle when the latter is picked and then moved to a position favorable for cooperation with the center filling stop fork.

In weft replenishing looms bobbin transfer ordinarily occurs when the lay is on front center and the freshly transferred bobbin is picked during backward motion of the lay when the latter is at or near its top center position. At the time of picking the thread of the incoming bobbin should be so located as to facilitate the first stage of shuttle threading as the shuttle moves toward the opposite side of the loom. Many looms are provided with a center filling stop motion fork under which a weft thread must pass to prevent loom stoppage. If the thread of the incoming bobbin is far to the rear in order to aid shuttle threading it is likely not to get under the fork and as a result the loom will be stopped.

It is an important object of the present invention to provide means which will place the thread of the transferred bobbin in a rearward position during part of the backward motion of the lay to assist the shuttle to thread, and thereafter during continued backward motion of the lay release the thread so that the shuttle due to its motion can cooperate with the thread holder to draw the thread forwardly and enable it to pass under the fork of the filling stop motion.

It is a more particular object of the invention to provide a thread moving member on the lay in front of the thread at the transferred bobbin to move the thread rearwardly during a part of the backward stroke of the lay, and in addition provide a cast off member, which may be upwardly and rearwardly inclined, to engage the thread and lift it from the moving member as the lay approaches its back center position, preferably while the shuttle is still in motion. The thread holder may if desired be of the pneumatic type, in which event the holder itself will exert a pull on the thread tending to move it under the filling fork, and when such a thread holder is used it is not so important that the thread be cast off the thread mover while the shuttle is in motion. When a non-retrieving thread holder is employed, however, it may be desirable to effect cast-off before the shuttle finally comes to rest in its travel across the lay.

With these and other objects in view which

2

will appear as the description proceeds, the invention resides in the combination and arrangement of parts hereinafter described and set forth.

5 In the accompanying drawings, wherein a convenient embodiment of the invention is set forth,

Fig. 1 is a side elevation of part of a weft replenishing loom having the invention applied thereto,

10 Fig. 2 is an enlarged front elevation looking in the direction of arrow 2, Fig. 1,

Fig. 3 is a vertical section on line 3—3, Fig. 2,

Fig. 4 is a plan view looking in the direction of arrow 4, Fig. 3, the thread collector being shown in section, and

Figs. 5 and 6 are diagrammatic views illustrating the manner in which the invention operates.

Referring particularly to Figs. 1 and 2, the loom frame 10 supports a reserve bobbin magazine M containing in the present instance front and back stacks 11 and 12 of reserve bobbins from which weft ends W extend to a thread holder H. The latter may be of the pneumatic type, although this is not essential for all uses of the invention, but when the holder is of that type it will be associated with an air pump 13 operated by the reciprocating lay 14 to create subatmospheric pressures in a tube 15 as the lay moves rearwardly. Tube 15 is connected to the top of a thread collector C the lower end of which is connected, as by a pipe 16, to the holder H. The collector is mounted on a base or support 17 carried by a bracket 18 secured as at 19 to the loom frame. The pneumatic system shown in Figs. 1 and 2 operates intermittently to create a partial vacuum in the thread holder H during backward motion of the lay, but the invention is not limited to an intermittently acting pneumatic thread holder.

The magazine includes in its construction a transerrer arm 20 having attached thereto a latch 21 normally below a bunter 22 on the lay but raised into the path of the latter when a replenishing operation is to occur to lower the transerrer arm and move the reserve bobbin under it into the shuttle S as the lay reaches front center. At the time of bobbin transfer the thread T of the freshly transferred bobbin, designated at B in Fig. 2, extends downwardly from the thread holder along a path inclined toward the center of the loom. As shown in Fig. 2 this thread is below any of the weft ends W leading from the untransferred bobbins in the magazine to the thread holder.

55 The loom is provided with picking mechanism

designated generally at 25 to pick the replenished shuttle S from the shuttle box 26 as the lay is moving rearwardly and is at or near its top center position.

The lay, see Fig. 6, is provided with a center filling fork 28 which operates in the usual manner and is mounted for pivotal motion on the front part of the lay forward of the path traversed by the shuttle when it is picked. This fork is ordinarily raised when the shuttle passes it and is lowered as the lay moves forwardly. If it falls on and is supported by a thread under it loom operation continues, but if there is no thread under the fork the latter continues its downward motion to effect loom stopping.

From the matter thus described it will be understood that bobbin transfer occurs when the lay is at its front center position, the thread T is detached from and below the group of weft ends W, the replenished shuttle is picked as the lay is at or near its top center position, and the shuttle continues to travel along the lay to the opposite side of the loom for a period of time which will ordinarily continue until after the lay has reached its back center position. While in its flight the shuttle passes behind the filling fork 28. During backward motion of the lay the thread T is subjected to pneumatic traction at the thread holder. The freshly transferred shuttle should be at least partially threaded during its pick immediately after replenishment, and the thread T should extend under the fork 28.

In carrying the present invention into effect the lay has secured thereto a thread moving member or the like designated at 30. This thread mover may be secured as at 31 to a part of the lay and has a rearwardly extending wing 32 the rear edge 33 of which traverses a path below the weft ends W but crossing the path of thread T. The upper end of rear surface or edge 33 may have a slight notch or detent 34 if desired. A cast-off or releasing member 35 is secured as at 36 to the base or stand 17 of the thread collector and has a finger 37 which is inclined downwardly and forwardly. This finger is offset from the moving member 30 in the direction of the length of the lay and extends upwardly to a point above the top of the thread mover 30. Its lower end is preferably below the thread T. The cast-off member 35 overhangs part of the lay as the latter approaches its rear or back center position.

In the operation of the invention a bobbin will be transferred into the shuttle as already described and will have its thread T extending from the thread holder down to the shuttle along a diagonal path in front of the cast-off member 35 and behind the thread mover 30. As the lay moves rearwardly, the thread holder remaining stationary, the mover 30 will overtake the thread T and move it rearwardly so that when the shuttle is picked when the lay is on top center position the thread will be kept in a position more or less in line with the shuttle as the lay continues to move rearwardly, thereby holding the thread T in a position favorable for the first step in the thread of the shuttle. After the shuttle has continued its flight along the lay far enough for the first threading step to have occurred the mover 30 will move the thread T up along finger 37 of member 35 and the latter due to the fact that it extends above the mover 30 eventually casts the thread T off the mover 30 as the lay approaches its rearmost position. The thread T is free to be straightened out partly by pneumatic attraction at the thread holder H and partly by reason of the

fact that the shuttle is continuing to move along the lay.

Figs. 5 and 6 indicate diagrammatically how the invention operates. With the lay on front center in position I, the thread T will be in the path of the mover 30 and as the lay moves rearwardly to picking position II the mover 30 overtakes and engages the thread and produces a bend in it as suggested in dotted lines Fig. 5. As the lay continues to move rearwardly to position III the member 35 will cast the thread off the mover 30 so that the thread extends from the holder H to the shuttle along some such path as indicated in dot and dash line a. As the shuttle continues to move it passes the filling fork and when the lay is in some such position as indicated at IV, Fig. 6, the thread T will be under the fork 28. The thread holder H is forward of the filling fork in position IV, and the shuttle in attempting to draw the thread in a straight line from the holder will draw it under the fork. When the holder H is of the pneumatic type there will be an additional force tending to draw the thread taut and under the fork.

The wing 32 of the mover 30 is purposely broadened as indicated for instance in Fig. 3 so that any whip of the thread as it is drawn toward the thread holder when subsequently cut will prevent the thread from wrapping around the thread mover.

From the foregoing it will be seen that the invention sets forth simple means including a thread mover on the lay and a cast-off member in stationary position effective to cause the thread of the transferred bobbin to remain in position favorable for shuttle threading during part of the backward motion of the lay subsequent to picking, and thereafter effective to release the thread so that it can be straightened sufficiently to pass under the filling fork 28. The thread can be attached either to a pneumatic thread holder H as shown herein, or any other convenient form of thread holder, but if the thread holder be of the non-retrieving type it is desirable that the casting off of the thread be effected while the shuttle is still in motion. This will ordinarily be true in the usual form of fly shuttle loom in which the shuttle is still in motion when the lay reaches its back center position.

Having thus described the invention it will be seen that changes and modifications of the foregoing specific disclosure may be made without departing from the spirit and scope of the invention.

What is claimed as new is:

1. In thread control means for a weft replenishing loom having a lay provided with a center filling stop fork and wherein a thread extends from a transferred bobbin in a shuttle on the lay to a thread holder, the shuttle being picked during backward motion of the lay and traveling along the lay as the latter moves to the back center position thereof, a thread moving member on the lay in front of said thread moving the latter rearwardly during part of the backward motion of the lay to facilitate threading of the shuttle, and a cast-off member effective as the lay approaches the back center position thereof to disengage the thread from the moving member, the shuttle due to motion thereof along the lay thereupon cooperating with the thread holder to draw the thread under the filling stop fork.

2. In a thread control for a weft replenishing loom having a reciprocating lay provided with a center filling stop fork and wherein a thread

extends from a thread holder to a freshly replenished shuttle on the lay, a thread moving member on the lay in front of the thread moving the latter rearwardly as the lay moves backwardly to facilitate threading of the shuttle incident to picking of the latter as the lay moves backwardly, and a cast-off member effective to disengage the thread from the moving member as the lay continues to move backwardly, the shuttle due to motion thereof subsequent to picking cooperating with the thread holder to move the thread under the filling stop fork.

3. In a weft replenishing loom having a lay provided with a center filling stop fork and wherein a thread extends from a thread holder to a freshly replenished shuttle on the lay, said thread to have a part thereof in one position relative to the lay favorable for threading of the shuttle when the latter is picked and said part of the thread to be in another position forward of said one position favorable for movement of the thread under said filling fork, a moving member on the lay in front of the thread moving said part of the thread to said one position during backward motion of the lay, and a releasing member effective as the lay continues to move backwardly to disengage said part of the thread from said moving member while the shuttle is in flight incident to picking thereof, the shuttle and thread holder thereupon cooperating to move said part of the thread to said other position thereof.

4. In a weft replenishing loom having a lay provided with a center filling stop fork and wherein a thread extends from a thread holder to a freshly replenished shuttle on the lay, said thread to be in one position relative to the lay favorable for threading the shuttle when the latter is picked and said thread to be in another position forward of said one position favorable for movement thereof under said filling fork, means on the lay engaging and moving the thread to said one position during backward motion of the lay, and stationary means effective during continued backward motion of the lay to disengage the thread from the first means while the shuttle is in flight, the thread holder and shuttle thereupon cooperating to move the thread to said other position.

5. In a weft replenishing loom having a lay provided with a center filling stop fork and wherein a thread extends from a thread holder to a freshly replenished shuttle on the lay, said thread to be in one position relative to the lay favorable for threading of the shuttle when the latter is picked and said thread to be in another position forward of said one position favorable for movement thereof toward said filling fork, means effecting positioning of the thread in said one position thereof while the shuttle is being picked, and means acting on the thread subsequent to picking of the shuttle enabling the latter while in flight to cooperate with the thread holder to move the thread to the other position thereof.

9625 9630 9635 9640 9645 9650 9655 9660 9665 9670 9675 9680 9685 9690 9695 9700 9705 9710 9715 9720 9725 9730 9735 9740 9745 9750 9755 9760 9765 9770 9775 9780 9785 9790 9795 9800 9805 9810 9815 9820 9825 9830 9835 9840 9845 9850 9855 9860 9865 9870 9875 9880 9885 9890 9895 9900 9905 9910 9915 9920 9925 9930 9935 9940 9945 9950 9955 9960 9965 9970 9975 9980 9985 9990 9995 9999

5. In a weft replenishing loom having a lay provided with a center filling stop fork and wherein a thread extends from a thread holder to a freshly replenished shuttle on the lay, said thread to be in one position relative to the lay favorable for threading of the shuttle when the latter is picked and said thread to be in another position forward of said one position favorable for movement of the thread under said filling fork, means effecting positioning of the thread in said one position thereof while the shuttle is being picked, and means acting on the thread subsequent to picking of the shuttle enabling the latter while in flight to cooperate with the thread holder to move the thread to said other position thereof.

6. In a weft replenishing loom having a lay provided with a center filling stop fork and wherein a thread extends from a pneumatic thread holder to a freshly replenished shuttle on the lay, said thread to be in one position relative to the lay favorable for threading of the shuttle when the latter is picked and said thread to be in another position forward of said one position favorable for movement thereof under said filling fork, and control means for the thread including a part on the lay in front of the thread and an upwardly and rearwardly inclined part back of the thread, said part on the lay engaging the thread and moving the latter to said one position and said other part thereafter engaging the thread and disengaging the same from the first part during backward motion of the lay, the shuttle due to motion thereof along the lay and the thread holder due to pneumatic attraction of the thread cooperating to move the thread to said other position thereof.
